COIFFURE RETAINING CAP

Filed Nov. 3, 1931

INVENTOR
M. Stone

BY HIS ATTORNEY *J. Ledermann*

UNITED STATES PATENT OFFICE

MAX STONE, OF NEW YORK, N. Y.

COIFFURE RETAINING CAP

Application filed November 3, 1931. Serial No. 572,791.

The main object of this invention is to provide a hair net which is adapted to be draped over the dressed hair of a woman and is used for the purpose of keeping the hair arranged while the person is robing or performing other duties.

Another object of this invention is to provide a hair net made of mesh material, which is constructed of two pieces and is provided with a constrictor band which snugly drapes the net over the hair.

The above and other objects will become apparent in the description below in which characters of reference refer to like-named parts in the drawing.

Referring briefly to the drawing, Figure 1 is a perspective view of the hair net as draped about the head of user.

Figure 2 is a rear elevational view of the device.

Figure 3 is a front elevational view of the hair net.

Referring in detail to the drawing, the numeral 10 indicates a semi-circular expanse of mesh material which comprises half of the hair net. A second similar piece of material 11 is complementary to member 10 and is joined to the latter by a row of stitching 13. Both members 10 and 11 have an internally formed hem 12 which lies concealed within the body of the cap. The ends of an elastic constrictor band 14 are secured to the rear of the cap above the open marginal edge thereof. Fluting 15 is formed at the front of the cap and has its center at the seam 13 at which position an ornament 16 is mounted. This fluting continues around half of the cap and serves to reinforce the front thereof.

The device in use is adapted to serve as a cap which is draped over the head and keeps the hair in dressed condition. The cap is fitted on the head by pulling the cap from front to rear. After the cap is snugly drawn over the head the band is permitted to tighten and thereby snap the cap in snug and draped position on the head.

It is to be noted that certain changes in form and construction may be made without departing from the spirit and scope of the invention.

I claim:

A hair net formed of two semi-circular members of netted material joined together, reinforcing material mounted at the front of said hair net extending from the marginal edge toward the center, hems in said hair net forming a cap, the seam joining said members extending from front to rear of the finished cap, and an elastic band secured to the marginal edge of said hair net for constricting the latter about the head of the wearer.

In testimony whereof I affix my signature.

MAX STONE.
